UNITED STATES PATENT OFFICE.

WILLIAM H. ROSE, OF JERSEY CITY, NEW JERSEY.

PROCESS OF MAKING CONTAINERS.

Application filed February 20, 1923. Serial No. 620,881.

To all whom it may concern:

Be it known that, I, WILLIAM H. ROSE, a citizen of the United States, and residing at Jersey City, Hudson County, State of New Jersey, have invented new and useful Improvements in Processes of Making Containers, of which the following is a specification.

My invention relates to containers and particularly to a process of making containers from paper or similar material and simultaneously attaching heads thereto.

The object of the invention is to provide a process by which the body of the container may be made from a strip of paper by rolling the same into tubular form and by which the heads for the container may be securely applied thereto during the operation of forming the body of the container.

My invention in its preferred form is illustrated in the accompanying drawings forming part of this specification and in which—

Fig. 1 is a perspective view showing a sheet of paper being wound on a mandrel in the process of forming the body of a container.

Fig. 2 is a fragmentary longitudinal section showing a head secured to the body of the container.

Figs. 3, 4 and 5 illustrate different forms of fastening means which may be employed for securing the heads to the body of the container.

In carrying out my invention I preferably proceed in the following manner:—I take a strip of paper 10 and wind a portion of the same upon a mandrel 11 this mandrel being rotated in any suitable manner and being of sufficient diameter to produce a container of the desired size. In this operation it is to be understood that a suitable glue is applied to the paper so that the various layers are securely glued together as they are wrapped about the mandrel. After a desired number of layers of paper have been rolled on the mandrel I then apply the heads to the partially completed body by slipping or forcing the same over the ends of the body. The heads which are designated by the num-

eral 12 are provided with a flange 13 which flange is adapted to surround and closely fit the partially completed body of the container. In order to permit the heads to be applied to the partially formed body on the mandrel, it is of course necessary either to provide notches in the edge of the strip of

paper material or in the flange 13 of the heads. In Figure 1 the strip 10 of paper material is shown notched at 14, which notches will of course permit application of a head 12 to each end of the partially completed body of the container. In Figures 3 and 5 the flange 13 of the head is shown provided with a slot 15 and where this expedient is employed it is of course possible to apply the heads to the incomplete body of the container without notching the edges of the paper strip. It is of course obvious that both the edges of the paper strip and the flange of the heads may be notched to a sufficient depth to permit the heads to be applied to the unfinished body of the container.

Various means may be employed for insuring strong attachment of the heads to the body of the container. In Figures 1 and 2 the flange 13 of the heads is shown provided with a series of openings 16 into which glue may penetrate thus producing an effective lock between the flange of the head and the inner and outer layer of paper material adjacent the flange. In Figure 3 the flange 13 is shown provided with a series of inwardly projecting prongs 17 which are adapted to engage and embed themselves in the paper material when the head is applied to the partially formed body. In this form the flange 13 is also provided with glue receiving openings 16. In Figure 5 the flange 13 is shown provided with a series of outwardly projecting prongs 18 and also with inwardly projecting prongs 17 like those of Figure 3. In this form it is of course evident that the inwardly projecting prongs will engage the partially formed body when the head is applied thereto and the outwardly projecting prongs will engage the material wound around the outside of the flange 13. In Figure 4 the flange 13 is shown provided with a serrated edge which is bent outwardly to provide a series of sharp prongs 19 which are adapted to engage the layers of paper material wound upon the flange 13. It is of course apparent that any desired combination of the foregoing fastening means may be employed.

After the heads are applied to the partially finished body of the container, it is to be understood that the rest of the paper strip 10 is wound around the portion of the container body previously produced and also over the flanges 13 on the heads. This winding is continued until the body of the con-

tainer outside of the flanges 13 is of the desired thickness, preferably being continued until the thickness of the body outside the flanges 13 is substantially equal to the width 5 of the radial flanges 12^a formed on the heads 12.

In order to permit application of the head 12 to the inner end of the body of the container such head must, as illustrated in 10 Figure 1, be provided with an opening 20 through which the stem of the mandrel passes. Preferably a head of this kind is placed on the stem of the mandrel before the 15 operation of forming the body begins. After the body is partially formed such head is then applied to the body as heretofore described and the opening 20 in such head provides for the application of the usual 20 cover or closure to the top of the container as indicated at 21 in Figure 2. It is of course not necessary to provide an opening such as 20 in the head which is applied to the outer or free end of the partially formed 25 container body, and such head may therefore form a solid bottom for the complete container.

Having thus described the invention what is claimed as new and desired to be secured by Letters Patent is:

20 1. The process of making a container from a continuous strip of paper material and simultaneously attaching a head thereto, which consists in rolling a portion of the 25 strip of paper material into the form of a tube, applying to such tube a previously formed head having a curved flange adapted to surround the end of the tube, said flange and the marginal portion of said strip being

constructed to permit said flange being slipped over the end of said tube, and then 40 rolling the rest of said strip of paper around said tube and said flange of the head.

2. The process of making a container from a continuous strip of paper material and simultaneously attaching a head thereto, 45 which consists in rolling a portion of the strip of paper material into the form of a tube, applying to such tube a previously formed head having a cylindrical flange adapted to surround the end of the tube, and extend inwardly from the edge of said strip, one of said parts, that is, said flange or the edge of said strip, being notched to permit said head being slipped over the end of said tube, and then rolling the rest of said 55 strip of paper around said tube and flange of the head.

3. The process of making a container from a continuous strip of paper material and simultaneously attaching a head thereto, 60 which consists in rolling a portion of the strip of paper material into the form of a tube, applying to such tube a previously formed head having a curved flange adapted to surround the end of the tube, said flange and the marginal portion of said strip being constructed to permit said flange being slipped over the end of said tube, and then 65 rolling the rest of said strip of paper around said tube and said flange of the head, said flange having means to provide interlocking engagement between the same and the paper material of the container.

In testimony whereof I hereunto affix my signature.

WILLIAM H. ROSE.
